UNITED STATES PATENT OFFICE.

ERWIN C. HUBBARD, OF GREEN BAY, WISCONSIN.

IMPROVEMENT IN PROPELLERS FOR VESSELS.

Specification forming part of Letters Patent No. 135,555, dated February 4, 1873.

To all whom it may concern:

Be it known that I, ERWIN C. HUBBARD, of Green Bay, county of Brown, Wisconsin, have invented a new and Improved Wheel for Propelling Vessels, of which the following is a specification:

This invention relates to that class of improvements which have for their object the propulsion of vessels when driven by steam or other motive power; and consists in a new form of shafts and blades, as will hereinafter be more fully described.

Figure 1 is a rear-end view of the wheel. Fig. 2 is a longitudinal section. Fig. 3 is a sectional detached view of the hub.

The devices forming the wheel are the shaft F, the conical hub E, the blades A, and arms B. The shaft F is inclosed in a sleeve, G. The conical hub E has curved serrated seats f, to which are attached the curved and tapering blades A, forming a conical-shaped wheel with apertures or openings, as shown at a. The sleeve may be made hollow, and, for the purpose of expelling the water more rapidly from the center of the wheel, is made tapering or larger at the end next the hub. B are stays or supports for the outer ends of the blades, and are fastened at one end to the sleeve, and the other end passes through the blades, with thread and nuts at either side, for the purpose of supporting the blades, and also to adjust the size of the openings between them.

In the drawing, four blades are shown. The number of blades is not material. There may be more or less, in proportion to the size of the wheel. The devices for regulating the space between the blades is important, inasmuch as the size of the openings gives the wheel more or less lead. The serrated seats upon the inner end of the hub, and upon which the small ends of the blades are fastened, are for the purpose of forming the openings at the small end of the wheel. The wheel may be placed at the stern, at the sides, or under the

vessel, and the propelling power may be applied to it in the ordinary way.

The advantage of this peculiar construction is that its force is centripetal, and it yields a vastly-increased amount of speed to the power applied.

In its practical operation the wheel receives the water through the apertures or openings between the blades. As the wheel revolves there is a constant pressure upon the whole of the inner surface of the blades, and the expulsion of the water forms a power of resistance in proportion to the velocity of the revolutions. It differs from the screw-propeller in the amount of surface acted upon by the water and in the amount of water displaced. This wheel is not designed to disturb or displace the water. On the contrary, the water is drawn into or clasped by the wheel, and when it is ejected therefrom it forms a powerful resisting force. By its peculiar construction and form it not only presents a small amount of resisting surface, but it has all the advantages of strength and durability, and it may be applied with equal success when it is desirable to use submerged wheels as side propellers. It is adapted to any description of navigation, whether ocean, lake, river, or canal. By simply reversing the wheel the boat may be backed with the same facility as the ordinary side-wheels or screws.

Having thus described my invention, what I claim, and desire to secure by Letters Patent, is—

A propeller or wheel having the shaft F, with or without the sleeve, the hub E with serrated seats f, tapering blades A forming the openings a, and the stays or supports B, constructed as described, and for the purposes set forth.

ERWIN C. HUBBARD.
